UNITED STATES PATENT OFFICE.

JOSEPH FLANAGAN THOMPSON, OF MARIETTA, OHIO, ASSIGNOR OF ONE-HALF TO
GEORGE H. SPINDLER, OF MARIETTA, OHIO.

EXTENSION CAR-STEP.

1,129,027.

Specification of Letters Patent. Patented Feb. 16, 1915.

Application filed November 23, 1914. Serial No. 873,547.

To all whom it may concern:

Be it known that I, JOSEPH FLANAGAN THOMPSON, a citizen of the United States, residing at Marietta, in the county of Washington and State of Ohio, have invented certain new and useful Improvements in Extension Car-Steps; and I do declare the following to be a full, clear, and exact description of the invention, such as will enable others skilled in the art to which it appertains to make and use the same.

This invention relates to car steps and more particularly to extension steps for cars.

The object of the invention is to provide a simply constructed, strong and easily operated extension step or steps which may be readily applied to the fixed steps already in use without any change being made in the latter.

20 With the above and other objects in view, the invention consists of certain novel features of construction, combination and arrangement of parts as will be more fully described and claimed.

25 In the accompanying drawings: Figure 1 represents a front elevation of a portion of a car equipped with this improved step, the step being shown in side elevation; Fig. 2 is a side elevation of the car showing the step in front elevation and with the extension member thereof raised; Fig. 3 is a longitudinal section taken on the line 3-3 of Fig. 2; Fig. 4 is a similar view showing the extension step in lowered operative position and the parts for operating it in the position which they assume when said step is so lowered; Fig. 5 is a horizontal section taken on the line 5-5 of Fig. 4; Fig. 6 is a rear elevation thereof.

40 In the embodiment illustrated, P represents the ordinary platform of a car and S the fixed steps leading therefrom having the usual rails R connecting the ends thereof. Removably mounted on these rails R and in alinement with the rear edges thereof seating snugly on said edges, is a frame 1 which carries an extension step 2 and its operating parts. This frame 1 consists of two side plates or rails 3 which are connected by cross bars 4 and 5, here shown disposed at the opposite ends of said rails. The lower ends of these rails 3 are inclined to correspond with the lower ends of the rails R with which they align when the at-

tachment is applied. The lower edges of these rails 3 are preferably curved as shown to provide longitudinally spaced projections 6 and 7, on the lower faces of the former of which are mounted shaft bearings 8 for a purpose to be described. This frame 1 is here shown connected with the rails R of the fixed or stationary steps of the car by means of two pairs of brackets 9 and 10 which are similarly constructed and disposed on opposite sides of the rails, each pair of brackets comprising L-shaped members 11 and 12 having their laterally extending arms provided with apertures for receiving a securing bolt 13, it being understood that one of each pair of brackets is mounted on the rail R and one on the rail 3 with the apertures in their laterally extending arms alining so that when the bolts 13 are passed therethrough and the nuts engaged with their ends, the frame 1 will be securely connected with the rails R of the stationary steps.

Guides 14 and 15 are secured to the inner faces of the rails 3 and extend longitudinally thereof, preferably throughout their entire length, said guides being here shown in the form of angle irons, substantially U-shape in cross section with the cross bars 16 thereof fixed to the rails 3 and their laterally extending arms or flanges 17 projecting inwardly and between which the side members of a sliding frame 18 are designed to operate.

The frame 18 is composed of side bars 19 and 20 which are of a width equal to the distance between the flanges 17 of the guides 14 and 15 and are adapted to slide in said guides. A cross bar or plate 21 connects the lower ends of these bars 19 and 20 and to which the extension step 2 is fixed, preferably by means of angle strips or plates 22 and 23 which are shown secured to the lower faces of the plate 21 and the step 2 respectively, whereby said step is securely fixed to the sliding frame 18. The plate 21 is here shown recessed at its inner edge midway its length and a stub shaft or rod 24 spans said recess and is designed to receive one end of a pitman 25 to be described. As shown, the side bars 19 and 20 of the sliding frame 18 are enlarged at their inner ends and are provided with depending stops 26, here shown in the form of pins which

are adapted to engage the cross bar 5 for limiting the outward or extension movement of the frame 18.

The step 2 projects at its opposite ends beyond the outer edges of the side bars 19 and 20 a distance equal to the thickness of the rails 3 and R and these ends are adapted when the step is in retracted position, to engage the lower edges of said rails and the upper face of the step 2 fits flat against the lower face of the lowermost step 9 of the fixed series. Reinforcing and guiding plates 27 and 28 are secured to the projecting ends of the extension step 2, being here shown 10 provided with laterally extending flanges 29 which are secured to the lower face of said step 2 adjacent its opposite ends and the body portions of these plates fit against the end edges of the step and against the outer faces 15 of the rails R and 3 and are of a length equal to the distance which said extension is designed to be projected so that said plates always engage the outer faces of said rails and thus guide the sliding frame and hold it 20 against lateral movement.

A shaft 30 is revolvably mounted in the bearings 8 on the lower faces of the projections 6 of the rails 3 and one end of said shaft projects beyond the outer face of the 25 adjacent rail 3 and is provided with a bevel gear 31 which is fixed thereto and is designed to mesh with a similarly shaped gear 32 carried by an upright standard or rod 33 revolvably mounted in suitable bearings carried by the rail 3, said rod having an operating wheel or handle 34 at its upper end positioned for convenient actuation by the conductor or other member of the train crew for a purpose to be described.

40 A plate or link 35 is fixed to the shaft 30 midway the ends thereof with one end projecting outwardly and the other inwardly, the inward end of said link being connected with the inner end of the pitman 25 and 45 which has a balance weight 36 secured thereto, said weight being designed to assist in the opening movement of the extension step and also performs the function of a spring engaging cam for holding the extension step 50 yieldably in retracted position. The spring 37 with which this weight is designed to cooperate is here shown in the form of a resilient strip secured at one end to the cross bar 4 and having an outwardly curved portion 55 therein arranged in the path of said balance weight 36 with its free end turned inward to facilitate the engagement of said weight with the outwardly bowed portion thereof. The free end of the link 35 may be connected 60 with a lever or series of levers disposed at any suitable point on the train or car for actuating the extension step at a point remote therefrom.

When it is desired to operate this extension step from the platform P of the car all

that is necessary is to turn the hand wheel 34 in the proper direction whereby the bevel gear 32 on its lower end meshing with the bevel gear 31 on the shaft 30, will impart a quarter turn to said shaft, thereby moving the weight carried end of the link 35 downward against the tension of the spring 37, thus moving the pitman 25 and the sliding frame 18 connected therewith downward or outward until the stops 26 engage the cross bar 5, whereby the extension step 2 will be projected in a plane below the lowermost of the fixed steps a suitable distance and after the passenger has alighted from the car, this step may be retracted by turning the hand wheel 34 in the opposite direction which will cause the cam weight 36 to ride up on the spring 37 until it passes the bowed portion thereof and it will be held in this position by said spring with the weight positioned over the shaft, thereby assisting and holding it in this position, the spring preventing its accidental downward movement.

Should the operator neglect to retract the step by turning the hand wheel 34, and said step should come in contact with a projection, it would be forced inward into closed position without in any way injuring any of the actuating parts thereof.

I claim as my invention:

1. The combination with fixed steps, of an extensible step slidably mounted relatively thereto, operating means for said sliding step including a cam member, a resilient locking element disposed in the path of said cam member and adapted to be engaged thereby when the sliding step is in retracted position, and means for retracting and projecting said sliding step.

2. A sliding extensible step comprising in combination with the fixed steps of a car, a frame, guides on said frame, an extensible step slidably mounted in said guides, means for said step including a cam member, a resilient strip disposed in the path of said cam member and having an outwardly bowed portion for engagement by said cam member when the step is in retracted position to yieldably hold it in said position, and means for retracting and projecting said step.

3. A sliding extensible step comprising in combination with the fixed steps of a car, a frame fixed to the sidings or rails of the steps, guides on the side members of said frame, an extensible step having laterally spaced arms extending rearwardly therefrom and slidably engaging said guides, means for limiting the sliding movement of the arms, operating means for said step comprising a revolvable shaft extending transversely of said frame, a link fixed to said shaft, a pitman connecting said step and link, a cam member carried by said link, a resilient locking element disposed in the

path of said cam and adapted to be engaged thereby when the step is in retracted position, and means for turning said shaft to retract or project said step.

5 4. A sliding extensible step comprising in combination with the fixed steps of a car, a frame fixed to the sidings or rails of the steps, guides on the side members of said frame, an extensible step having laterally spaced arms extending rearwardly therefrom and slidably engaging said guides, means for limiting the sliding movement of the arms, operating means for said step comprising a revoluble shaft extending transversely of said frame, a link fixed to said shaft, a pitman connecting said step and link, a cam member carried by said link, a resilient strip secured to said frame in the path of said cam and having an outwardly bowed portion for engagement by said cam when the step is in retracted position to yieldably hold it in said position, and means 10 for turning said shaft to retract or project said step.

20 5. A sliding extensible step comprising in combination with the fixed steps of a car, a frame fixed to the sidings or rails of the

steps, guides on the side members of said frame, an extensible step having laterally spaced arms extending rearwardly therefrom and slidably engaging said guides, means for limiting the sliding movement of the arms, operating means for said step comprising a revoluble shaft extending transversely of said frame, a link fixed to said shaft, a pitman connecting said step and link, a cam member carried by said link, a resilient strip secured to said frame in the path of said cam and having an outwardly bowed portion for engagement by said cam when the step is in retracted position to yieldably hold it in said position, and means 15 for turning said shaft to retract or project said step.

In testimony whereof I have hereunto set my hand in presence of two subscribing witnesses.

JOSEPH FLANAGAN THOMPSON.
